Corporation, Worcester, Mass., a corporation of
Massachusetts

Application November 14, 1940, Serial No. 365,604

5 Claims. (Cl. 22—68)

The present invention relates to machines for casting molten metal, molding heat plasticizable material, under pressure, and has for its object to provide an improved mechanism for operating the relatively movable die carrying members of such a machine.

The mechanism of the present invention is particularly characterized by the provision of a rigid frame of such open form as to provide ample space for the reception of large dies, or dies having long pull cores in any direction. Furthermore, the frame is adapted to support, as a unit, the entire operating mechanism for the movable die plate, so that the distance between die plates can be readily and accurately adjusted within a considerable range, to accommodate different sizes of dies. Furthermore, the entire linkage arrangement for operating the movable die plate is continuously lubricated under pressure, thereby contributing to the ease of operation of the machine and greatly reducing maintenance due to the wear of moving parts.

The above and other advantageous features of the invention will hereinafter more fully appear from the following description with reference to the accompanying drawings, in which:

Fig. 1 is a view in side elevation of a casting machine embodying the invention.

Fig. 2 is a plan view of the parts shown in Fig. 1.

Fig. 3 is a vertical sectional view along the line 3—3 of Fig. 1, looking in the direction of the arrows.

Fig. 4 is a vertical sectional view along the lines 4—4 of Fig. 1, looking in the direction of the arrows.

Fig. 5 is a half sectional view, on an enlarged scale, of the operating assembly for the movable die plate.

Fig. 6 is a plan view of a portion of the parts of Fig. 5, illustrating the lubrication of the operating linkage.

Fig. 7 is a fragmentary sectional view along the line 7—7 of Fig. 1, looking in the direction of the arrows.

Referring to the drawings, the machine provides a frame 1 mounted on a base B, and comprising an end member 2 and spaced side members 3 connected by tie bars 4 extending from the corners of the end member 2, as best shown in Fig. 3. A fixed die plate 5 is integral with the end member 2, and a gate opening 6 therein is in communication with the delivery openings 7 of any suitable device for supplying molten or plasticized material under pressure, such as a

sleeve 8 from which the material is forced by a plunger 9 operated from cylinder 10.

A second die plate 11 is slidably mounted for movement on the frame 1 by means of guides 12 cooperating with horizontal ways 13 fixed to the upper and lower tie bars 4. The die plate 11 also provides a pair of heavy side guides 14 slidable in gibs 15 provided by the side members 3 of the frame. The die plate 11 is thus guided at the top and bottom, as well as the sides, for movement on the rigid members of the frame 1, so that the slotted surface thereof, on which is mounted the movable die, is always maintained in substantially parallel relation with respect to the slotted surface of the die plate 5 on which is mounted the stationary die. Dies D are indicated in dotted lines in Fig. 1, and it is evident that the distance between the die plate 11 and the right-hand ends of side members 3 of the frame is such that a considerable range of die thicknesses may be employed.

As best shown in Fig. 5, the die plate 11 is adapted to be moved back and forth with respect to the fixed die plate 5, by means of cooperating sets of toggle links 16, 17 and 18, operated by means of a cross head 19. The links 16 and 17 are pivotally connected to the die plate 11 and to the cross head 19, respectively, by pins 20 and 21, and to each other by pins 22, and provision is made for supporting and lubricating these pivot pins, as will later be described. The links 18 are pivotally connected to the other links 16 and 17 by the pins 22, while their opposite ends are connected by pins 23 to lugs 24 provided by a member 25, in the form of a yoke, which is adapted to support the entire operating assembly for the die plate 11.

As shown in half section, the yoke member 25 provides a central opening 26, in which is received one end of a cylinder 27, having a piston 28 movable therein, when the cylinder is supplied with a fluid pressure medium. The piston 28 carries a rod 29 extending through the inner end of the cylinder between the lugs 24 and connected at its end to the cross head 19 for operating the toggle linkage. As best shown in Fig. 4, the cross head 19 provides lateral extensions 30 slidably supported between gibs 31, received in a slot 32 provided in each side guide 14 of the movable die plate 11. Therefore, the cross head 19 is supported for straight line movement between the sets of toggle links 16, 17 and 18 in any position of the movable die plate 11, due to the fact that the guides 14 extend for a distance considerably greater than the maximum length of travel of

the cross head 19, indicated by the dotted and full line positions of Fig. 5.

As best shown in Fig. 7, the yoke member 25 carrying the operating mechanism for the die plate 11, provides wings 33, on which are formed 5 guides 34 bearing on ways 35 extending above and below the gibs 15. Thus, the weight of the entire assembly for operating the die plate 11 is borne by the rigid side members 3 of the frame 1, and the invention contemplates an improved 10 arrangement, whereby the entire assembly carried by the member 25 can be adjusted with respect to the frame 1 to vary the distance between the relatively movable die plates 5 and 11.

To this end, the left-hand end of the frame 1 provides fixed adjusting screws 36, extending 15 freely through openings 37 provided in arms 38 extending from the member 25 above and below the lugs 24, see Fig. 5. The threaded portion 38a of each screw 36 carries a nut 39 that is rotatably 20 connected to an arm 38 of the member 25, by means of a collar 40 engaging a groove 41 formed on the nut 39. The nut 39 provides a flange 42 extending beyond the collar 40, to which is secured a worm gear 43, by means of which the 25 nut 39 may be turned to exert a shifting force of the arm 38 with respect to the fixed screw 36.

Each worm gear 43 is in mesh with a worm 44 mounted on a shaft 45, and as best shown in Fig. 1, the shafts 45 are in alinement, and are connected together for rotation in unison by means of a sleeve coupling 46. The lower shaft 45 provides suitable gearing 47, whereby the coupled shafts 45 may be turned together by means of a crank applied to an operating shaft 48. In this way, both nuts 39 may be turned in unison, to cause the entire assembly carried by the member 25 to be shifted with respect to the frame 1, whereby the spacing between the die plates 5 and 11 may be varied accurately within a considerable range to accommodate dies of different heights.

The utilization of two adjusting screws located above and below the center line of the frame 1, makes it possible to obtain the desired locking pressure for dies which may be off center with relation to the die plates 5 and 11, a condition which is sometimes unavoidable. While normally both nuts 39 are turned in unison when making an adjustment in the distance between the die plates, removal of the coupling 46 permits independent adjustment of either nut 39 so as to effectively compensate for any pronounced off center relation of the dies with respect to the plates, such as would require a greater pressure above 55 or below the center line of the frame.

As previously pointed out, provision is made for lubricating the several pivot pins 20 to 23, inclusive, of the linkage mechanism which moves the die plate 11. As best shown in Figs. 5 and 6, oil under pressure is supplied by a pipe P to a duct 49 extending through a lug 24, which duct is in communication with a passage 50 extending axially through a pin 23, and closed at its ends 60 by plugs 51. Radial ducts 52 leading from the passage 50 are in communication with grooves 53 provided in bearings 54 located between the lugs 24 and the links 18.

Each link 18 provides a passage 55 in communication with a duct 52, so that the oil is conducted by these passages 55 to the ends of a passage 56 extending through each pin 22. Radial ducts 57 leading from the passage 56 distribute 70 the lubricant to bearings 54a, and to passages 75

58 extending through the links 16. The passages 58 conduct the oil to a passage 59 extending through each pin 20, from which radiate ducts 60 supplying the bearings 54b.

Each link 17 connecting links 16 and 18 to the cross head 19, provides a passage 61 communicating with a duct 57 in a pin 22, whereby the lubricant is conducted to a passage 62 extending axially of the pin 21. Ducts 63 radiating from the passage 62, lubricate the bearings 64 of each pin 21. Thus the entire linkage system for operating the die plate 11, is thoroughly lubricated at all times under pressure, thereby substantially eliminating frictional losses in the die closing operation, and greatly increasing the life of the machine, as well as reducing maintenance thereof.

It is evident from a consideration of Figs. 4 and 6, that the several sets of pivot pin bearings 54, 54a and 54b, are spaced evenly across the width of the die plate 11, both above and below the cross head 19. The bearings are thus adapted to relieve the pivot pins 20, 22 and 23 of the load when the dies are closed, and their symmetrical arrangement with respect to the center line of the frame, insures the maintenance of a parallel relation between opposed surfaces of the die plates 5 and 11, respectively.

We claim:

1. A pressure casting machine comprising in combination, a frame providing spaced parallel top and bottom members rigidly connected by side members, a die plate guided at its corners between said top and bottom frame members, guide bars carried by said die plate extending rearwardly from opposite sides of said die plate and slidably supported in ways provided by said side frame members, a yoke member supported between said side frame members and providing portions extending above and below said guide bars, a cross head slidably supported by said guide bars, and operating linkage connecting said cross head to said die plate and said yoke member.

2. A pressure casting machine comprising in combination, a frame providing spaced parallel top and bottom members rigidly connected by side members, a die plate guided at its corners between said top and bottom frame members, guide bars carried by said die plate extending rearwardly from opposite sides of said die plate and slidably supported in ways provided by said side frame members, a yoke member supported between said side frame members and providing portions extending above and below said guide bars, a cross head slidably supported by said guide bars, operating linkage connecting said cross head to said die plate and said yoke member, and means cooperating with said yoke member for adjusting, with respect to said frame, the entire assembly consisting of said die plate, guide bars, cross head and linkage connections.

3. A pressure casting machine, comprising in combination a rigid frame providing an end member for supporting a stationary die plate, a second die plate, parallel spaced side members provided by said frame and carrying ways for slidably supporting in the space between them said second die plate, by means of guide bars extending rearwardly from opposite sides of said plate, a yoke member supported by said frame side members at the end of the frame opposite to said stationary die plate, and extending between said side members in the direction of said

second die plate, a cross head slidably supported between the guide bars of said second die plate, a cylinder provided by said yoke member for operating said cross head, connections between said cross head, said second die plate and said yoke member, and means for adjusting said yoke member with respect to said frame to move, as a unit, said yoke member, together with its connections to said second die plate, whereby to regulate the distance between said die plates.

4. A pressure casting machine, comprising in combination a rigid frame providing an end member for supporting a stationary die plate, a second die plate, parallel spaced side members provided by said frame and carrying ways for slidably supporting in the space between them said second die plate, by means of guide bars extending rearwardly from opposite sides of said plate, a yoke member supported by said frame side members at the end of the frame opposite to said stationary die plate, and extending between said side members in the direction of said second die plate, a cross head slidably supported between the guide bars of said second die plate, a cylinder provided by said yoke member for operating said cross head, connections between said cross head, said second die plate and said yoke member, means for adjusting said yoke member with respect to said frame, comprising threaded studs carried by said frame between its side members, nuts cooperating with said studs and rotatably mounted on said yoke, and means for turning said nuts in unison to shift

said yoke member, as a unit, including its connections to said second die plate, to vary the distance between said die plates.

5. A pressure casting machine, comprising in combination a frame comprising spaced parallel top and bottom members rigidly connected by side members, and providing an end member for supporting a stationary die plate, a second die plate guided at its corners for movement between said top and bottom frame members, guide bars carried by said movable die plate extending rearwardly from opposite sides of said die plate, a yoke member supported between said frame side members at the end of the frame opposite to said stationary die plate and having portions extending in the direction of said movable die plate, a cross head slidably supported on the guide bars of said movable die plate, a cylinder carried by said yoke member for operating said cross head, connections between said cross head, said movable die plate and said yoke member for causing relative movement between said die plates and the maintenance of pressure between engaged dies carried by said plates, and means for adjusting said yoke member with respect to said frame to move, as a unit, said yoke member, together with its connections to said movable die plate, to regulate the distance between opposed faces of said die plates for the accommodation of different sizes of dies.
